UNITED STATES PATENT OFFICE

JOSHUA M. RICHARDS, OF BROOKLINE, MASSACHUSETTS

SKYLIGHT CONSTRUCTION

Application filed January 11, 1932. Serial No. 585,874.

The present invention relates to skylight construction whereby a lighting structure may be used with a monolithically cast roof slab constructed by the so-called "Pan" or "Grid" system of reinforced concrete, also known as one-way and two-way reinforcing systems.

Heretofore the construction of skylights by the above systems has been such that it has been necessary to leave an opening in the roof coextensive with the size of the lighting unit. This opening causes a weakening of the roof of "Pan" or "Grid" construction because it breaks the unity of the reinforcement by preventing the proper placing of the reinforcing steel, and this weakening makes necessary external supporting structures of various types to bolster the skylight otherwise unsupported. The use of ordinary skylights has heretofore made necessary changing the design of the roof slab, resulting in an unsightly ceiling because of the external supports for areas lighted by skylights, causing interference with pipes, conduits, and other appliances located near the roof, and also marring the appearance of the molded soffit of the roof slab.

The principal object of the present invention is to produce a skylight construction in which the reinforcing system of the roof slab is not interfered with despite the existence of lighting openings.

A further object of the present invention is to produce a skylight construction eliminating the weakening found in constructions made heretofore due to the absence of concrete in the roof area for the skylight.

A further object of the present invention is to produce a skylight construction in which no external supporting members are needed to support the skylight.

A further object of the present invention is to produce a skylight construction which will not interfere with the continuity of the contour of the soffit of the roof, or with pipes, conduits, etc., which may be located near the soffit.

A further object of the present invention is to provide a skylight construction with a "Pan" or "Grid" reinforcing system in which

no additional costs are involved in the method of erecting the roof slab.

Other features of the present invention consist in certain combinations and arrangements of parts hereinafter described, and then pointed out broadly and in detail in the appended claims possessing advantages readily apparent to those skilled in the art.

The various features of the present invention will be readily understood from an inspection of the accompanying drawing illustrating the best form of the invention known to the inventor, in which,

Fig. 1 is a view in plan of a skylight and a portion of the adjacent roof;

Fig. 2 is an enlarged detail in sectional elevation of the skylight and roof, taken along the line 2-2 of Fig. 1, and

Fig. 3 is a detail view in elevation of the skylight, roof, and roof supports, showing the projection of the skylight above the upper surface of the roof.

The illustrated embodiment of my invention exemplifies a roof and skylight construction in which a skylight is incorporated with a monolithically cast roof slab which extends over the entire span of the bay to be covered.

The illustrated embodiment of my invention is provided with one or more panes of plain or wired glass 4, either square or rectangular in shape. These panes may vary in number, depending upon the amount of overhead light necessary or upon the space available for such light. The skylight construction shown in Fig. 1 shows a unit of thirty-five panes. Each pane 4 is set in a frame 5 which completely surrounds the frame. The frame 5 is best constructed of some non-rusting metal. The panes 4 are secured to the frames 5 by some elastic and waterproof material 6, so that when the glass expands and contracts breakage and leakage are prevented, respectively.

The panes and the frames so secured to them are set in a support 7 made of reinforced concrete, the whole forming a light transmitting unit, constructed in a manner hereinafter described. The concrete support 7 is reinforced in the usual manner by metal bars or rods 8 and 9 which in the best con-

struction extend both transversely and longitudinally within the pane-supporting concrete.

The parts thus far described form, as a unit, the skylight part of a roof. This skylight superstructure rests upon a portion 11 of the roof 10 prepared for it. The roof 10 is a monolithically cast slab of reinforced concrete. When the roof 10 is cast, the manner of the casting being described hereinafter, the portion 11 of the roof supporting the skylight is cast higher than the upper surface of the roof proper. The whole roof casting has the usual reinforcing bars or rods 13 which run both longitudinally and transversely. The transverse rods only are shown in Fig. 2. The portion 11 of the roof casting extending above the upper surface of the roof proper is also reinforced in the usual way by rods or bars 12 which run both transversely and longitudinally through the casting. Only the transverse rods are shown in Fig. 2.

The function of the raised portion 11 of the roof casting is to furnish skylight support which an unraised portion can not furnish. In ordinary skylights the absence of concrete in the entire skylight opening takes away the necessary support against the compression of the skylight. The embodiment of my invention, however, does not eliminate concrete under the skylight, but utilizes it there, reinforced by rods or bars, so that provision is made for the necessary concrete to support the skylight, at the same time providing skylight openings to light areas below.

It will be seen that such a construction eliminates the need for external supporting structures such as are now seen in buildings provided with skylights. The entire support does not extend below the soffit of the roof. The roof is cast with the kind of soffit desired, and nothing disturbs its continuity, or interferes with overhead pipes, conduits, shafting or other appliances.

With such a construction a means must be provided so that no harm will come to the skylight, especially when covering a large area, caused by the expansion and contraction prevalent in reinforced concrete. In large areas this expansion and contraction, if unguarded against, will cause cracks, resulting in the leakage of water. Because such cracks would appear in the skylight, I have made my skylight construction such that the reinforced skylight unit rests upon the monolithically cast roof slab, completely unbonded with it. In this way the roof slab can contract and expand freely, yet not harm the skylight unit.

Inspection of Fig. 3 shows that the skylight, extending only above the roof, presents a curb construction which allows drainage of snow and rain. To insure that no water may leak through between the periphery of the

skylight and that part of the roof slab which immediately supports it, a curb flashing 14 is provided to form a waterproof contact. This curb flashing 14 may be made of roofers' sheet copper or of any other material suitable for flashing. One end of the flashing extends into the lower face of the peripheral portion of the reinforced concrete of the skylight, as shown at 15. The flashing 14 then extends between the lower face of the peripheral portion of the skylight concrete and the upper peripheral face of the supporting portion of the roof slab, passing down the external wall of the supporting portion of the roof slab. The flashing extends over the roof slab to form a waterproof sheath, and is secured by a tack 16, or any suitable fastening means, to a strip of wood 17 or other material suitable to receive it, set in the concrete of the roof slab when the slab is cast.

It will be seen that with such a construction the entire roof including the skylight is made waterproof, and at the same time there is no bond between the skylight and the roof slab. The skylight is insulated from it.

In constructing the roof slab with the skylight openings 18 builders' templates or forms usual for such construction are placed as desired with their bottom faces even, flat, and at the same grade. The supporting means for the templates has the surface that the soffit of the roof is to have. Where the skylight openings are to be located the templates are higher. Reinforcing is then placed in the usual way, and the concrete is poured. Where the skylight templates occur, the concrete is poured to a higher level, but not over the top of the templates. The other templates are of course covered by the concrete. The concrete about the templates which form the skylight openings is poured to the height necessary to provide concrete for supporting the skylight to compensate for that which has been eliminated by the skylight openings.

In constructing the skylights over the openings in the roof slab, the panes 4 are set in the non-rusting frames 5, and are secured thereto by some waterproof, elastic substance 6. The frames and panes, placed as desired, are then cemented together with reinforced concrete 7, forming a skylight unit such as is shown in Fig. 1. The frames 5 have a surface construction next to the concrete 7 such that they are supported by the concrete, and form a waterproof contact with it. One example of such construction is shown in frame 5 in Fig. 2.

The upper surface of the roof slab may be covered with a tar and gravel covering 20, or with any other substance used in roof surface construction.

The difference in depth between the templates forming the unapertured portion 19 and the apertured portion 18 of the roof slab 10 is shown as it is in Fig. 2 for purposes of

description only. It is apparent that how far the skylight extends above the roof slab proper depends upon the size or nature of the roof, and may vary with different needs

5 without in any way departing from the principle of the invention.

Nothing herein explained is to be interpreted as limiting the various features of the present invention in the scope of its application to use in connection with the particular skylight or the particular mode of construction or both selected for the purpose of illustration and explanation. While the particulars of construction herein set forth are 10 well suited to one form of the invention and to the use to which it is put, it is not limited to this use, nor to these details of construction, nor to the conjoint use of all its features, nor is it to be understood that these 15 particulars are essential, since they may be modified within the skill of the artisan without departing from the true scope of the actual invention, characterizing features of which are set forth in the following claims 20 by the intentional use of generic terms and expressions inclusive of various modifications.

What is claimed as new, is:

1. In a skylight construction, the combination with a plurality of light transmitting panes and a reinforced concrete construction supporting the panes, of a monolithically cast apertured roof slab supporting the pane-supporting construction the upper surface of the apertured portion of said slab contacting substantially the entire under face of the pane supporting construction.

2. In a skylight construction, the combination with a plurality of light transmitting panes, metal frames therefor, and a waterproof and elastic binder for panes and frames, all set in reinforced concrete to constitute a unitary construction, of a monolithically cast apertured roof slab supporting said unitary construction the upper surface of the apertured portion of said slab contacting substantially the entire under face of the concrete of said unitary construction.

3. In a skylight construction, the combination with a light transmitting unit including a plurality of panes, of a monolithically cast apertured roof slab supporting the light transmitting unit and unbonded with it the upper surface of the apertured portion of said slab contacting substantially the entire lowermost surface of said light transmitting unit.

4. In a skylight construction, the combination with a plurality of light transmitting panes, metal frames therefor, and a waterproof and elastic binder for panes and frames, all set in reinforced concrete to constitute a unitary construction, of a monolithically cast apertured roof slab supporting said unitary construction and unbonded with it the

upper surface of the apertured portion of said slab contacting substantially the entire under face of the concrete of said unitary construction.

5. In a skylight construction, the combination with a light transmitting unit including a plurality of panes, of a monolithically cast roof slab having an unapertured portion, and an apertured portion for supporting the light transmitting unit, the upper surface of said apertured portion contacting substantially the entire lowermost surface of said light transmitting unit, and the lowermost surface of said apertured portion being on the same grade as the lowermost surface of said unapertured portion.

6. In a skylight construction, the combination with a light transmitting unit including a plurality of panes, of a monolithically cast roof slab having an unapertured portion, and an apertured portion for supporting the light transmitting unit, the upper surface of said apertured portion contacting substantially the entire lowermost face of said light transmitting unit, and the continuity 80 of the lowermost portions of the entire slab being unbroken.

7. A skylight construction having, in combination, a light transmitting unit including a plurality of panes, and a monolithically cast roof slab comprising an unapertured portion and an apertured portion extending above the upper surface of the unapertured portion for supporting the light transmitting unit the upper surface of said apertured portion contacting substantially the entire lowermost surface of said light transmitting unit.

8. A skylight construction having, in combination, a light transmitting unit including a plurality of panes, and a monolithically cast roof slab for supporting the light transmitting unit, said slab comprising an unapertured portion and an apertured portion the upper surface of which extends above the upper surface of the unapertured portion and contacts substantially the entire lowermost surface of the light transmitting unit, the lowermost surface of said apertured portion being uniform with the lowermost surface of said unapertured portion.

9. In a skylight construction, the combination with a light transmitting unit including a plurality of panes and a monolithically cast roof slab of reinforced concrete for supporting the light transmitting unit, said slab comprising an unapertured portion and a portion having a plurality of apertures, of means integral with said apertured portion and above the level of the upper surface of said unapertured portion for providing sufficient concrete to compensate for that lost because of the apertures.

10. A skylight construction having, in combination, a light transmitting unit in-

cluding a plurality of panes, a monolithically cast apertured roof slab supporting said unit and unbonded thereto the upper surface of the apertured portion of said slab contacting substantially the entire lowermost surface of said light transmitting unit, and a flashing, a portion of which extends between said slab and unit, for waterproofing the abutment of said slab and unit.

19 11. A skylight construction having, in combination, a light transmitting unit including a plurality of panes, a monolithically cast apertured roof slab supporting said unit and unbonded thereto, the upper surface of the apertured portion of said slab contacting substantially the entire lowermost surface of said light transmitting unit, and a curb flashing extending around the periphery of that portion of said slab abutting said unit for waterproofing abutment of said slab and unit.

12. A skylight construction having, in combination, a light transmitting unit including a plurality of panes, a monolithically cast apertured roof slab supporting said unit and unbonded thereto the upper surface of the apertured portion of said slab contacting substantially the entire lowermost surface of said light transmitting unit, and a curb flashing, secured to said slab, extending around the periphery of that portion of said slab abutting said unit for waterproofing the abutment of said slab and unit.

13. A skylight having, in combination, a monolithically cast apertured roof slab, a waterproof curb flashing surrounding the periphery of said slab, and a light transmitting unit including a plurality of panes, said unit being supported by said slab and unbonded with it and the upper surface of the apertured portion of said slab contacting substantially the entire lowermost surface of said light transmitting unit.

In testimony whereof I have signed my name to this specification.

JOSHUA M. RICHARDS.
